(57) **CLAIM**

The ornamental design for a reciprocating saw, as shown and described.

DESCRIPTION

FIG. 1 is a first perspective view of a reciprocating saw showing my new design;

FIG. 2 is a second perspective view of the reciprocating saw shown in FIG. 1;

FIG. 3 is a side view of the reciprocating saw shown in FIG. 1;

FIG. 4 is a top view of the reciprocating saw shown in FIG. 1;

FIG. 5 is a bottom view of the reciprocating saw shown in FIG. 1;

FIG. 6 is a front elevational view of the reciprocating saw shown in FIG. 1; and,

FIG. 7 is a rear elevational view of the reciprocating saw shown in FIG. 1.
